UNITED STATES PATENT OFFICE.

ROBERT S. BOLGER, OF NEW YORK, N. Y., ASSIGNOR TO INTERNATIONAL MOTOR COMPANY, OF NEW YORK, N. Y., A CORPORATION OF DELAWARE.

MOTOR-TRUCK SPRINKLER AND FLUSHER.

Application filed July 13, 1920. Serial No. 395,964.

To all whom it may concern:

Be it known that I, ROBERT S. BOLGER, a citizen of the United States, residing in New York city, in the borough of Manhattan, 5 city of New York, in the State of New York, have invented certain new and useful Improvements in Motor-Truck Sprinklers and Flushers, of which the following is a specification, reference being had to the 10 accompanying drawings, forming a part hereof.

In motor truck sprinklers and flushers one desirable construction involves the control of the water pump through the main vehicle 15 clutch. One objection to such construction, however, is that when the main clutch is thrown out no power is applied to the water pump and, further, the pump pressure varies directly with the vehicle speed. It has been 20 proposed to employ a construction in which the crank shaft is connected through an independent clutch with the pump shaft, but this construction is somewhat involved mechanically, requires a duplication of parts, 25 and is more expensive. The object of the present invention is to provide means in association with sprinklers and flushers, for maintaining the nozzle pressure even when the pump itself is disconnected from the 30 driving shaft or has its speed reduced. In accordance with the present invention there is provided an auxiliary pressure regulating tank in which a supplemental supply of water is maintained under constant pressure 35 and is discharged under such pressure automatically whenever the pump pressure falls. This auxiliary regulating tank receives water from the main vehicle tank and has such water stored up under pressure derived from 40 the main water pump during normal operation thereof. The improved construction is at once simple, relatively inexpensive, and mechanically certain, being automatic in its regulation. Reference is to be had to the accompanying drawings for detailed description 45 of two suitable embodiments of the invention in which—

Figure 1 is a view in side elevation of so much of a motor truck sprinkler and flusher 50 as is necessary for an understanding of the present improvements.

Figure 2 is a view, somewhat schematic, and in perspective, of a somewhat modified arrangement of tanks.

55 The main water tank *a* is provided with a

filler opening *b* through which water is received and a discharge pipe *c* leading to a water pump *d*. The pump *d* may be driven from the propeller shaft *d'* of the vehicle, the rotation of this propeller shaft being 60 controlled by the main vehicle clutch *f*, all in a manner well known. The water pump *d* discharges through a pipe *e* to the sprinkler and flusher nozzles *g* located in any desirable arrangement to the vehicle and constructed 65 in any approved manner. Each of these nozzles *g* is carried on a pipe *g'* in which may be mounted a manually operated cut-off valve *g''*. From the pipe *e* leads a pipe section *e'* to an auxiliary pressure regulating 70 tank *h* constructed and mounted on the vehicle frame in any desired manner. The tank *h* preferably communicates with the atmosphere through a vacuum valve *h'* which closes the tank port when the pressure 75 within exceeds atmospheric pressure. Between the pump *d* and the branch pipe *e'* is preferably provided, in the pipe *e*, a check valve *i* of any approved type. Between the branch pipe *e'* and the nozzles *g* is preferably mounted a pressure regulating valve *k* by which the nozzle pressures are limited at 80 all times.

When the main tank *a* is filled water is free to flow into the auxiliary regulating 85 tank *h* under the pressure of the head within the tank *a* and until the valve *h'* is seated by the pressure within the tank *h*. With the hand valves *g''* opened and the pump *d* operating water will be discharged past the reducing valve *k* to the nozzles *g* at the predetermined pressure for which the valve *k* is set. This pressure will usually be substantially lower than the pump pressure with the result that a quantity of water is pumped 95 through the branch pipe *e'* into the tank *h* until the pressure within the tank is substantially equal to the pump pressure. Accordingly, when the pressure of the pump *d* falls to any degree the water within the pipe *e* passing through the reducing valve *k* will be subject to the additional pressure impressed thereon from within the tank *h*. Indeed, when the pump *d* is stopped entirely the flow of water from within the tank *h* 105 through the branch pipe *e'* and the nozzles *g* will continue at relatively high pressures decreasing constantly, however, until no greater than the pressure for which the reducing valve *k* is set. It will be understood, 110

of course, that since the auxiliary pressure tank is entirely of a reserve character it will not ordinarily be called on to furnish a supplemental supply for such an appreciable time as to exhaust the pressure therein. The reserve tank will be useful such times as the vehicle is actually stopped or the pressure of the pump *d* for some reason reduced. At no time will the pump be subject to any counter pressure from the auxiliary tank by reason of the check valve *i*.

The modified arrangement shown in Figure 2 is illustrative of a practical construction embodying the principle of the invention. The main water tank *A* is provided with a filler opening *B* and communicates through a discharge pipe *C* with a water pump *D*. Instead of a single auxiliary pressure regulating tank there are provided two tanks *H* disposed at opposite sides of the tank *A* and connected through branch pipes *E* with the main discharge pipe *E*. The other features of construction and operation correspond with those described with particularity in connection with the construction illustrated in Figure 1.

Other ways of practising the invention

will suggest themselves to one skilled in the art but all modifications entailing mere mechanical skill are to be deemed within the scope of this application provided the advantageous results are realized in substantial accordance with the principles herein set forth.

I claim as my invention:

In a motor truck sprinkler and flusher in combination, a main water tank, a sprinkler pipe communicating with the main tank, a pump in the sprinkler pipe, an auxiliary pressure regulating water tank, a pipe connection from the auxiliary tank to the sprinkler pipe, a check valve in the sprinkler pipe between the pump and said pipe connection, a vacuum valve in the auxiliary tank operable at atmospheric pressure to close the said tank to the atmosphere, and a pressure reducing valve in the sprinkler pipe between the said pipe connection and the discharge end of the sprinkler pipe, said pressure reducing valve being set for pressures below the normal pump pressure.

This specification signed this ninth day of July A. D. 1920.

ROBERT S. BOLGER.
